United States Patent Office.

JOHN ADAMS, OF ROCHESTER, NEW YORK.

Letters Patent No. 96,649, dated November 9, 1869.

IMPROVED APPARATUS FOR CARBONIZING PEAT.

The Schedule referred to in these Letters Patent and making part of the same

To all whom it may concern:

Be it known that I, JOHN ADAMS, of the city of Rochester, county of Monroe, and State of New York, have invented a certain new and useful Improvement in Carbonizing Peat, to be used for marking-ink and other useful purposes; and I do hereby declare that the following is a full and exact description thereof, reference being had to the accompanying drawings, making part of this specification, in which—

Figure 1 is an elevation of my improved apparatus.

Figure 2, a vertical cross-section of the same.

Figure 3, a plan.

Like letters of reference indicate corresponding parts in all the figures.

My invention consists in carbonizing peat, for making into marking-ink and other useful products, by placing the same in an apparatus of peculiar construction, and treating substantially as hereinafter described.

In the drawings—

A A represent furnaces of any ordinary construction, having grates *a a* and ash-chambers *b b*.

In the furnaces are placed closed retorts B B, which enter endwise, and rest in such a position as to leave a clear and unobstructed passage for the heat all around.

The outer ends of these retorts are made removable, for the purpose of inserting and removing the peat to be acted on.

Over the furnaces is situated a steam-boiler, C, having a water-supply pipe, *c*, and safety-valve *d* at one end, and an exit-steam pipe, *f*, at the other.

Each of the retorts has also a steam-pipe, *g*, opening through the head, and each of the furnaces a steam-pipe, *h*, opening therein.

All these pipes, *g g* and *h h*, are arranged in a circle struck from the centre of pipe *f*.

The pipes *g g* and *f* are provided with ordinary stop-cocks *i i*.

A curved pipe, D, is connected with steam-pipe *f*, by means of a swivel-clamp, *k*, and also with any one of the other steam-pipes, by a similar swivel-clamp, *k*.

By this means the pipe D, turning on centre *f*, can swing and connect with any or all of the pipes *g g h h* in succession, to let in steam to the retorts and furnaces, to extinguish the fires, as indicated by the dotted lines in fig. 1.

The steam-boiler is covered by a jacket, G, which

concentrates the waste heat passing through flues *m* from the furnaces.

From the jacket the heat and smoke pass off into the ordinary boiler-chimney.

The peat in its crude state is first dried and then sifted, and then placed in the retorts B B, and subjected to heat, as described, till thoroughly carbonized. In doing this, it is brought to a red heat.

When the proper degree of carbonization is attained, the swing-pipe D is turned from one pipe to another of the pipes *g g h h*, and the fire at once extinguished or deadened in both the retorts and the furnaces, when the charge can be at once removed and replaced, and the same operation performed again with but little loss of time or fuel.

The arrangement of pipes, as above described, is very effective for accomplishing this result.

Beside the mechanical advantage of letting steam into the retorts, to extinguish the fires therein, I claim a great advantage in its chemical action upon the carbonized material, in revivifying it and giving it life.

This treatment I believe to be new.

It is obvious that instead of steam, gas—for instance, carbonic-acid gas—may be ejected from the boiler to extinguish the fires.

This carbonized product may be applied to a great variety of purposes, such as making marking-ink for expressmen, forwarders, &c., and moulders' facings; also, a superior substitute for ordinary lamp-black. In this respect, it is much blacker and of better quality than the ordinary products of wood, treated in a similar manner.

Mixed with the ordinary elements, it also produces a superior paint.

What I claim as my invention, and desire to secure by Letters Patent, is—

The carbonization of peat, by means of the apparatus, consisting of the furnaces A A, retorts B B, and boiler C, said parts being provided with pipes *f g g h h*, connected by swing-pipe D, the whole arranged as described, and operating in the manner and for the purpose specified.

In witness whereof, I have hereunto signed my name, in the presence of two subscribing witnesses.

JOHN ADAMS.
